UNITED STATES PATENT OFFICE.

WILLIAM J. KENNEY, OF CHICAGO, ILLINOIS, ASSIGNOR TO UNDERFEED STOKER COMPANY OF AMERICA, OF CHICAGO, ILLINOIS, A CORPORATION OF NEW JERSEY.

FURNACE.

1,172,290.

Specification of Letters Patent. Patented Feb. 22, 1916.

Application filed June 13, 1910. Serial No. 566,534.

To all whom it may concern:

Be it known that I, WILLIAM J. KENNEY, a citizen of the United States, residing at Chicago, county of Cook, State of Illinois, 5 have invented a certain new and useful Improvement in Furnaces, and declare the following to be a full, clear, and exact description of the same, such as will enable others skilled in the art to which it pertains to 10 make and use the same, reference being had to the accompanying drawings, which form a part of this specification.

Difficulty is experienced in furnaces having brick walls adjacent to the grate or 15 other support for a bed of fuel, in that clinkers adhere to the walls; this being particularly objectionable where the clinkers and ashes are to be discharged adjacent to one of the walls so that an adhering mass of 20 clinkers at this point interferes with the ejecting means.

The principal object of my invention is to produce an arrangement of furnace walls which will prevent the adherence of clinkers 25 thereto.

A further object of my invention is to produce a simple and novel furnace construction which shall be efficient in operation and durable.

30 The various features of novelty whereby my invention is characterized will herein-after be pointed out with particularity in the claims; but for a full understanding of my invention, and of its object and ad- 35 vantages, reference may be had to the following detailed description taken in connection with the accompanying drawings, wherein:

Figure 1 is a longitudinal section through 40 a furnace arranged in accordance with a preferred form of my invention; Fig. 2 is a view partly in plan and partly in section; Fig. 3 is a transverse section taken near the extreme front end of the furnace; Fig. 4 is 45 a section taken on line 4-4 of Fig. 3; Fig. 5 is a section on an enlarged scale through one of the side walls of the furnace and the adjacent portion of the fuel supporting means; and Fig. 6 is a view similar to Fig. 50 1 showing a modification.

Referring to Figs. 1 to 5 of the drawings, A represents a furnace having side walls A' and A'', a front wall A³ and a rear wall A⁴. Within the furnace are two retorts B 55 and B' forming parts of well known types

of underfeed stokers, the tops of the retorts being inclined downwardly from the front to the rear. Each of the side walls of the furnace has an overhanging portion extending into proximity to the adjacent retort and serving to support one side of a dead plate closing the gap between it and the retort. In the arrangement shown, the overhanging portions are composed in part of members a' and a'' which may be made of masonry or other material of which the walls are constructed, together with metallic member C and C' which lie between the members a' and a'', respectively, and the retorts. In rear of the retorts is a hollow bridge wall D, 60 preferably of cast iron. The members C and C' extend from the front wall of the furnace to the bridge wall and they may conveniently be supported by means of I-beams E and E' and beams F and F', the latter 65 being illustrated as being in the form of channel irons. The beams E and E' are embedded at their front ends in the front wall of the furnace and at their rear ends rest against the front of the bridge wall. The 70 members F and F' are also embedded at their front ends in the front wall of the furnace, while at their rear ends they are supported upon low piers G and G'. The 75 members are supported from beneath upon girders, H and H', while the rear ends thereof rest upon a transverse girder I which may conveniently extend between the piers and have its ends embedded therein as indicated at i. The members a' and a'' of the 80 over-hanging portions of the side walls extend back to the rear of the bridge wall so that the space beneath the same communicates with the interior of the bridge wall 85 through the open ends thereof.

J is a plate extending downwardly from the rear ends of the retorts to the bottom of the furnace; this plate extending from pier to pier so as to form the rear wall of an air-well beneath the retorts. As will be seen, 90 most clearly in Figs. 2 and 5, each of the retorts has laterally projecting flanges b at the top thereof, these flanges being provided with openings b' extending therethrough.

B² are twyler blocks arranged upon the flanges, along the inner edges thereof, the blocks being held in place by means of ears b² which extend down through the openings b', the ears being as wide as the openings so as to hold the blocks against play, but 105 110

being thin so as not materially to obstruct the opening. These twyer blocks may be of any suitable construction and will therefore not be described in detail.

- 5 Between each retort and the adjacent wall of the furnace is a dead plate, these being indicated at K and K'. Each of these dead plates rests upon the flange of the adjacent retort on the outside of the twyer blocks 10 and upon a laterally projecting flange c on the metallic portion of the adjacent side wall. The members K and K' are slideable lengthwise of the furnace and are provided with pivoted dogs k which are adapted to be 15 raised and lowered as the plates are reciprocated. All of the dogs associated with each dead plate are connected together by a long bar K² which is in turn connected with an operating crank K³ by means of a link K⁴. 20 When the crank arms K³ are oscillated, the two dead plates are reciprocated and the dogs are oscillated, so that the clinkers and ashes which are deposited upon the dead plates are fed toward the rear end of the 25 furnace. Between the two retorts is a third dead plate K^o which may be similar to the other two and need not, therefore, be specifically described. These dead plates and the actuating means therefor are similar to 30 those described and claimed in an application filed by Henry P. Grohn and myself on October 12, 1908, Serial No. 457,199; and therefore, since the present invention does not depend upon any particular dead plate 35 construction, I deem it unnecessary further to describe the construction illustrated.
- The member I is spaced apart from the bridge wall so that an ash chute is formed by these members and the plate J, together 40 with the two piers, directly in rear of the retorts. Thus the piers G and G' and the members I and J serve as partition walls co-operating with the bridge wall to form a discharge passage or ash chute separated 45 from the air chamber below the retorts. This ash chute may open into a suitable pit A⁶. Upon the top of the member I is a piece I' having a shearing edge parallel with the bridge wall.
- 50 L is a reciprocable shearing member mounted between the member I and the bridge wall so as to coöperate with the member I to break or shear the clinkers when they are fed rearwardly beyond the stationary member. As seen in Fig. 2, the bridge wall is provided with T-shaped guide lugs d² on its front face while the member L is provided with correspondingly shaped slots l' which receive the guide lugs. Consequently 55 the member L may be moved up and down along the front of the bridge wall without danger of being displaced. The member L may be connected to crank arms M by means of links l so that when the 60 crank arm is oscillated the member L will

be reciprocated. I prefer to incline the front face of the bridge wall so as to bring it approximately at right angles with the dead plates and thereby cause the shearing member to reciprocate in a path at right angles 70 to the dead plates. The crank arms M may be connected to or form part of a transverse shaft M' mounted in suitable bearings M² beneath the member I. By properly proportioning the bearing members M² they 75 may be made to serve as supports upon which the member I rests, so that the member I is supported not only at its ends but also at intermediate points. The shaft M' is provided with a crank arm M³, and a connecting rod M⁴ extends between this crank arm and a crank arm N' formed upon or secured to the transverse shaft N. The crank arms K³ are secured to a transverse shaft K⁶ which is provided with a downwardly projecting crank arm K⁶. The shaft 80 N has an upwardly projecting crank arm N² which is connected to the arm K⁶ by means of a link N³. The shaft N is oscillated in any suitable manner as, for example, by means of a piston rod N⁴ connected to the arm N'. It will be seen that as the piston rod reciprocates, the shaft N is oscillated so that the feeding mechanism for 85 the clinkers and ashes is moved back and forth and the moving shearing member caused to travel up and down.

It will be seen that the space beneath the retorts and the dead plates, the space beneath the over-hanging walls, and the space 100 within the bridge wall are intercommunicating so as to form a large air chamber into which air may be forced under pressure to supply to the furnace the air necessary for combustion. It will furthermore be 105 seen that the air in this chamber comes in contact with the metal walls projecting above the retorts and the dead plates in front and at the sides thereof so that a cooling action on these walls is produced 110 and they are prevented from warping or burning out under the intense heat of the furnace. This permits the walls to be made of a material, such as cast iron, to which the partly molten clinkers will not adhere, 115 so that the clinkers and ashes will readily travel toward the rear end of the furnace and there be discharged through the ash chute without danger of clogging. The air may be supplied in any suitable manner, but 120 I prefer to introduce it into the interior of the bridge wall, at which point the heat is probably the greatest. This may conveniently be accomplished by placing a large air conduit O beneath the floor of the furnace room at a point adjacent to the bridge wall and providing a large connecting passage O' between the conduit and the bottom 125 of the bridge wall. It will thus be seen that air under pressure flows from the conduit 130

into the bridge wall, there surges into contact with the heated surfaces and finally emerges from the open ends of the bridge wall into the space beneath the overhanging portions of the side walls of the furnace where it comes in contact with the metallic members C and C' and cools these also. Thereafter the air flows beneath the dead plates and the retorts and finally passes upwardly into the combustion chamber through the twyer blocks. In the arrangement shown, the conduit O lies somewhat in rear of the bridge wall so that the air flowing through the passage O' impinges directly against the hottest portion of the bridge wall. A damper O² may be placed within the passageway O' so as to regulate the flow of air.

The specific furnace which I have illustrated is one in which the width of the furnace is considerably greater than the necessary width of the fuel-support, so that a large addition to the air space beneath the retorts is afforded by the overhanging portions a' and a² of the furnace walls. It is evident that where there is less room in the furnace, the depth of the overhanging portions a' and a² may of course be diminished, or these portions may be eliminated, leaving only the metallic members C and C'.

In Fig. 6 I have illustrated a modification in which the furnace P is provided with two stokers or sets of stokers arranged end to end with a hollow bridge wall Q between them. R and R' represent the fuel-supporting members of the two stokers which terminate a short distance from the bridge wall. S and S' are ejecting members for clinkers and ashes arranged between the bridge wall and the members R and R' respectively. Air may be introduced into the hollow bridge wall through a suitable pipe T. In the particular arrangement shown, there is no communication between the interior of the bridge wall and the air chambers U and U' beneath the members R and R' and therefore, in order to insure circulation of the air within the bridge wall, I provide it with an opening q which will permit some of the air to escape into the combustion chamber. q' is a gate or valve associated with the port or opening q for the purpose of varying the effective size of this opening when desired. In this arrangement as in the other the bridge wall may be made of cast iron to which the clinkers will not adhere, so that the clinkers and ashes may readily be ejected at the rear ends of the stokers.

While I have described in detail only two preferred forms of my invention, I do not desire to be limited to these particular forms or to the details of construction illustrated and described; but intend to cover all forms and arrangements which fall within the

terms employed in the definitions of my invention constituting the appended claims.

What I claim is:

1. In a furnace, a support for a bed of fuel arranged within the furnace, a hollow bridge wall arranged in rear of and spaced apart from the support, means arranged between the bridge wall and said support for discharging clinkers and ashes downwardly from the support, a partition wall at each side of said support adjacent to the bridge wall, a third partition wall at the rear of said support, the partition walls extending downwardly so as to confine the discharging clinkers and ashes to the space directly in rear of the support, metal walls projecting above said support at each side thereof, there being passageways leading from the ends of the hollow bridge wall around the outside of the said metallic walls and the side partition walls and into the space beneath said support, and means for introducing air into the interior of said bridge wall.

2. In a furnace, a support for a bed of fuel extending across the same and dividing it into two compartments comprising an upper combustion chamber and a lower air well, a hollow bridge wall arranged in rear of and separated from said support, a downwardly extending partition at the rear of said support for closing the rear end of the air well and forming with the bridge wall a discharge chute for the reception of clinkers and ashes from said support, and there being passageways leading from the ends of said bridge wall into the air well so as to form an air space including both the interior of the bridge wall and the air well, and means for introducing air into said space.

3. In a furnace, a support for a bed of fuel arranged in the furnace, and separating it into a combustion chamber and an air well, a downwardly extending partition wall at the rear end of said support for closing the rear end of the air well, a hollow open-ended bridge wall in rear of said support and spaced apart from said partition wall, two side walls arranged between the ends of said partition wall and of said bridge wall so as to form a discharge chute for clinkers and ashes in rear of said support, there being passageways connecting the sides of the air well with the ends of said bridge wall so as to form an air space including the air well and the interior of the bridge wall, and means for introducing air into said space.

4. In a furnace, a support for a bed of fuel arranged in the furnace and separating it into a combustion chamber and an air well, a downwardly extending partition wall at the rear end of said support for closing the rear end of the air well, a hol-

- low open-ended bridge wall in rear of said support and spaced apart from said partition wall, two side walls arranged between the ends of said partition wall and of said bridge wall so as to form a discharge chute for clinkers and ashes in rear of said support, there being passageways connecting the sides of the air well with the ends of said bridge wall so as to form an air space 5 including the air well and the interior of the bridge wall, means for introducing air into said space, and means arranged within said chute for ejecting clinkers and ashes into the same.
- 10 5. A furnace having side walls undercut on the inner sides thereof so as to form longitudinally-extending over-hanging portions, a support for a bed of fuel extending between said over-hanging portions so as to divide the furnace into a combustion chamber and an air well, a downwardly extending partition wall at the rear end of the support for closing the rear end of the air well, a hollow bridge wall arranged 20 in rear of said support and spaced apart from said partition wall, means extending between the ends of said partition wall and bridge wall for forming therewith a discharge chute in rear of said support and 25 separated from the air well, the ends of said bridge wall opening into the space beneath said over-hanging portions outside of said chute so as to form an air chamber including the space beneath said support 30 and said over-hanging portions and the space within said bridge wall, and means for introducing air into said air chamber.
6. A furnace having side walls undercut on the inner sides thereof so as to form longitudinally-extending over-hanging portions, a support for a bed of fuel extending between said over-hanging portions so as to divide the furnace into a combustion chamber and an air well, a downwardly extending partition wall at the rear end of the support for closing the rear end of the air well, a hollow bridge wall arranged in rear of said support and spaced apart from said partition wall, means extending between the 40 ends of said partition wall and bridge wall for forming therewith a discharge chute in rear of said support and separated from the air well, the ends of said bridge wall opening into the space beneath said over-hanging portions outside of said chute so as to form an air chamber including the space beneath said support 45 and said over-hanging portions and the space within said bridge wall, and means for introducing air into said air chamber.
7. A furnace having side walls undercut on the inner sides thereof so as to form longitudinally-extending over-hanging portions, a support for a bed of fuel extending between said over-hanging portions so as to divide the furnace into a combustion chamber and an air well, a downwardly extending partition wall at the rear end of the support for closing the rear end of the air well, a hollow bridge wall arranged in rear of said support and spaced apart from said partition wall, means extending between the 50 ends of said partition wall and bridge wall for forming therewith a discharge chute in rear of said support and separated from the air well, the ends of said bridge wall opening into the space beneath said over-hanging portions outside of said chute so as to form an air chamber including the space beneath said support 55 and said over-hanging portions and the space within said bridge wall, and means for introducing air into said air chamber, and means associated with said support for moving the clinkers and ashes resulting from combustion toward said chute.
8. In a furnace, two separated beams extending lengthwise within the furnace near each side thereof, the outermost beams being arranged above the inner beams, a support for a bed of fuel arranged within the furnace and resting at its sides upon the inner beams, a hollow metallic bridge wall arranged in rear of and projecting above said support, metal side walls resting upon each pair of beams and with the said support dividing the furnace into an air well and a combustion chamber, there being passages leading from the interior of the bridge wall 60 into the space beneath the side walls, and means for introducing air under pressure into the interior of the bridge wall.
9. In a furnace, a support for a bed of fuel having passages therethrough for permitting air to flow into the bed of fuel from points beneath the support, a hollow open-ended bridge wall in rear of said support and projecting above the same, the bridge wall with the side and front walls of the furnace forming a closed air chamber a portion of which lies directly on the under side of said support, the side walls of the furnace being undercut in the vicinity of the said support so as to extend said air chamber laterally beyond the sides of said support, the side portions of said air chamber extending back to the bridge wall and communicating with the interior thereof, and means for introducing air under pressure into the interior of said bridge wall.
10. In combination, a furnace, a retort for fuel arranged within the furnace, supports beside the retort for receiving clinkers and ashes therefrom, said retort and said sup-

ports coöperating to divide said furnace into an upper combustion chamber and a lower air chamber, a hollow metallic bridge wall spaced apart from the rear end of the retort and the supports and projecting above the same, means for forcing air under pressure through said hollow bridge wall, mechanism for delivering fuel to said retort, means for feeding clinkers and ashes along said supports toward said bridge wall and means slidable up and down along the face

of the bridge wall for positively forcing the clinkers and ashes down into the space between the bridge wall and said supports as the clinkers and ashes are delivered in proximity to said space. 15

In testimony whereof, I sign this specification in the presence of two witnesses,

WILLIAM J. KENNEY.
